(57) **CLAIM**

The ornamental design for finger exerciser, as shown and described.

DESCRIPTION

FIG. 1 is a front perspective view of a finger exerciser, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 shown in FIG. 3;

FIG. 10 is a front view of a finger exerciser shown in environmental use; and,

FIG. 11 is another view of a finger exerciser shown in environmental use.

The broken lines in the drawings illustrate the portions of the finger exerciser that form no part of the claimed design.

The broken line showing of a hand in FIGS. 10 and 11 depicts environmental subject matter and forms no part of the claimed design.

The dot-dash lines shown in FIG. 3 illustrate the location and direction of the cross-sectional view shown in FIG. 9.
